UNITED STATES PATENT OFFICE.

GEORGE WILLIAM ODELL, OF WESTMOUNT, QUEBEC, CANADA.

RECORDING-MACHINE FOR MECHANICALLY-DETERMINED CALCULATIONS.

1,250,494.

Specification of Letters Patent. Patented Dec. 18, 1917.

Original application filed August 26, 1914, Serial No. 858,591. Divided and this application filed February 19, 1916. Serial No. 79,450.

To all whom it may concern:

Be it known that I, GEORGE WILLIAM ODELL, a subject of the King of Great Britain, and resident of 202 Girouard avenue, 5 Westmount, in the Province of Quebec, in the Dominion of Canada, have invented certain new and useful Improvements in Recording-Machines for Mechanically-Determined Calculations; and I do hereby declare 10 that the following is a full, clear, and exact description of the same.

The invention relates to recording machines for time and distance calculating machines as described in the present specification and illustrated in the accompanying drawings that form part of the same.

The invention consists essentially of the novel means employed, whereby the mechanism is operated by the peculiar shape of an 20 instrument in the form of a card suitable for the calculation of a workman's time, distances, heights, speeds and other uses.

The objects of the invention are to devise a comparatively simple and sure means of 25 recording on a card or other-like surface the result of the measurement of a card or the like, prepared in a preliminary machine to act as a tool in the recorder, to eliminate the human liability to errors in various calculations by effecting the same mechanically, to facilitate the carrying out of the routine in factories and other establishments, to enable 30 scientists, travelers and constructors to measure distance, speed and time with accuracy and despatch and generally to provide an efficient means for the purpose.

In the drawings, Figure 1 is a plan view of the machine.

Fig. 2 is a side elevation of the machine.

40 Fig. 3 is a longitudinal sectional view of the base.

Fig. 4 is a front elevation of the machine.

Fig. 5 is a plan view of the base.

45 Fig. 6 is a detail of the lock for the operating rack.

Fig. 7 is a detail showing the inking ribbon and shield.

Fig. 8 is a plan view of the operating instrument in the form of a card.

50 Fig. 9 is a fragmentary view of a type ring showing groups of time and quantity types.

Like numerals of reference indicate corresponding parts in each figure.

Referring to the drawings, the base 1 is 55 reduced in width for the greater part of its length forming the shoulder 2, and adjacent to the front end, the transverse trip recess 3 extends downwardly and connects with the channel 4, the latter terminating in the 60 transverse dog recess 5 about midway in the length of said base 1.

The disks 6 are pivoted near their upper ends on the transverse spindle 7 extending across the recess 3 and with the pins 8 form 65 trips in the operation of the mechanism. The said disks 6 at their lower ends are connected to the stops 9 pivotally mounted on the spindle 10 extending across the stop recess 5, said stops gradually increasing in 70 length respectively from one side of the recess to the other, and each stop being connected by a rod 11 to a disk 6. The pins 8 extend upwardly beyond the surface of the base 1, so that any flat instrument pushed 75 along said surface will flatten the pins downwardly thus turning the disks on their pivot and throwing the stops rearwardly.

The arms 12 project laterally from the base 1 slightly forward of the stop recess 5 80 and at each end carry the spring arms 13, the latter forming shaft sockets 14 at the upper ends. The post 15 projects upwardly from the upper end of one of the spring arms 13 and has attached thereto the 85 spring 16.

The shaft 17 is secured in the sockets 14 and on this shaft the roll 18 is journaled, said roll being formed of the type rings 19, carrying the type 20 separated by the pins 90 21.

The post 22 projects upwardly from the shaft 17 and is slidably arranged thereon, said roll 18 being secured to said post 22 in such a manner as to avoid bringing the latter with said roll in rotation.

The spring 16 is secured to the post 22 and is always in tension, consequently the roll will always have the tendency to slide toward the fixed post 15.

100 The type rings 19 are of different diameters so that the different lengths of the stops will reach correspondingly or fail to reach, as the case may be.

The roll 18 is mounted on the shaft 17, so that the spring 23 brings the roll normally back to zero as far as the type are concerned, consequently a pawl 24 is spring-
5 held to one or other of the pinions 21 during operation and is thrown back during the turning and transverse movements of said roll by the contact of the pivoted rack bearing 25 with the arm 26 in engagement with
10 said pawl.

The rack bearing 25 is in the form of a sleeve having the lug 25^a pivotally secured by the pin 27 to the side of the base 1 intermediately of the distance between the
15 front end and shoulder 2, said sleeve being normally held in an inclined position by the spring 28 secured to said base.

The rack 29 slides in the bearing 25 and at its front end has the thumb knob 30. 20 Toward its rear end the rack has a groove 31, which registers with the rib 32 on the bracket 33 extending upwardly from the base 1, said rib terminating before it reaches the base, so that the rack is free in its horizontal position and locked in its inclined position. The said rack when brought to its horizontal position meshes with one or other of the said pinions, and in drawing it forward the roll 18 is rotated to the extent of
25 30 the travel of said rack.

The permanent stop 34 stands up from the base at the front end, and its front face is level with the front end of said rack when the latter is in its zero position, which corresponds with the zero position of the roll 18.

The card 35 is the instrument or tool for operating the machine and at the same time for receiving the record in time and quantity as the type on the type rings of the roll 40 18 are arranged preferably in characters in groups, one set 41 of each group denoting the time elapsed and the other 42 denoting the value of the time or other quantity, and while the time type are in horizontal alignment and correspond on the several type rings, the quantity type represent different rates or calculations on each ring, therefore though in the rotation of the roll the time type on each roll will correspond, the particular ring over the base will show the rate for that time, that is wanted for the record.

The card 35 is previously prepared by another device and is here shown as clipped at each side, the strips taken away being different lengths and consequently leaving shoulders 36 and 37 at different depths in the card, and it is the distance between these depths that determines the time, for in its use the card is inserted under the roll 18, one shoulder 36 being against the permanent stop 34, while the rack is drawn up to the shoulder 37, until its outer end abuts said shoulder, then the roll 18 is turned the proper distance to bring around for print-

ing purposes the time type corresponding to the distance longitudinally between the shoulders 36 and 37.

The rate or quantity is determined by the longitudinal slot 38 in the card, as said slot forms a path for one of the trip pins 8, thus leaving a stop 9 undisturbed, and this particular stop reaches forward just far enough to stop a type ring over the base in printing position behind the opening in the ribbon shield 39, the latter shielding the adjacent type from also printing through the ribbon 40.

Briefly the purpose and operation may be further explained:—

The card is first clipped on one side and 80 then on the other at a later hour in another machine or in any suitable way, and the joining piece near the outer end of the slot 38 torn away to leave a free passage for one of the pins, said slots 38 being arranged 85 at that part of the card corresponding to the particular type ring, that is to say, there are different cards for different rates, and where the machine is used in factories, the rate of charge for the job is first determined and that particular card given to the workman.

The slot is of course only one way of fixing the card for an escapement mechanism and it must be understood that any 95 construction in laterally driving, rotating or stopping the roll may be used so long as it is within the scope of the claim for novelty following and of course the card will be made to correspond to the machine. 100

The rack on being drawn up to the shoulder 37 turns the roll 18 and at the same time releases the pawl 24 during the turning operation, coincidently the spring drawn roll 18 slides along the shaft until held by 105 one of the stops 9, which engages its corresponding type ring and holds it in position for printing. The roll which is very near the card is then pressed down by the yielding of the spring arms 13 on to the 110 card and the time and rate printed. The rack is then moved back to its zero position, and consequently the roll also returns to its zero position, in readiness for the next operation.

This application accompanies a separate application for a card filed under Serial Number 79,451.

What I claim is:—

In a recording machine for mechanically 120 determined calculations, a stamping mechanism, having a type member provided with characters indicating time and quantity in grouped arrangements, and a card stop, said machine being adapted to receive a record 125 card clipped at the sides to form shoulders at different depths and having an irregularity intermediate of the width for select-

ing the correct quantity on the insertion of said card, and coöperating means adapted to engage the free shoulder of said card at the completion of its movement for bringing to printing position the correct time and quantity group of type corresponding to the formation of the card.

Signed at Montreal, Quebec, Canada, this 31st day of December 1915.

GEORGE WILLIAM ODELL.
